PHOTOCOPIER CABINET

Yves Cormier, 100 Rue Hoche, 72000 Le Mans, France

Filed Dec. 12, 1973, Ser. No. 424,045

Term of patent 14 years

Int. Cl. D16—03

U.S. Cl. D61—1 Q

FIG. 1 is a right side elevational view of a photocopier cabinet showing my new design, the side opposite being substantially a mirror image;

FIG. 2 is a top plan view thereof;

FIG. 3 is a front elevational view thereof;

FIG. 4 is a rear elevational view thereof;

FIG. 5 is a front perspective view thereof; and,

FIG. 6 is a rear perspective view thereof.

The bottom of the photocopier cabinet is substantially plain and unornamented.

I claim:

The ornamental design for a photocopier cabinet, substantially as shown and described.
